WADDLING TOY OBJECT

Reginald C. Requa, Cold Spring Harbor, N. Y.

Application September 10, 1946, Serial No. 695,857

4 Claims. (Cl. 46—105)

1

My invention relates to a toy object having a waddling motion simulating the motion of a duck. Among the purposes and objects are to provide the following:

A simple cam motion operated by the wheels on which the object is carried when pulled along a plane surface such as a floor to cause a waddling or tilting and swinging motion simulating the waddling of a duck.

A plane oblique end cam and means for revolving the cam to cause a waddling motion of the object moved by the cam.

An object supported, in part, on a revolving cam shaft in which the object has an aperture which is countersunk to provide a point bearing to compensate for the tilting swinging motion of the object.

A toy object having a part with parallel sides to engage the flat oblique end surface of a cam to cause the object to tilt when the cam is revolved.

I accomplish these and other objects by the construction herein described and shown in the drawings forming a part hereof in which:

Fig. 1 is a top perspective view.

Fig. 2 is a fragmentary perspective view of the cam and cam shaft axle.

Fig. 3 is a front perspective view showing the tilting and the swinging motion of the object in broken lines.

Fig. 4 is a top perspective view of a modification.

Fig. 5 is a cross sectional view of the modification shown in Fig. 4, taken on the vertical centerline of the cam shaft axle.

Similar reference characters refer to similar parts throughout the several views of the drawings and in the specifications.

General description

I am aware that toys having objects made to move by a cam or crank operated from the axle on which the toy object is supported are not new. The toy object may swing or tilt but not waddle. By waddling, as the word is used in this disclosure, I mean the combined motion of tilting and swinging as, for example, the motion of a duck while waddling or walking. The figure, when drawn along the floor, simulates the motion of a waddling duck. The cam faces produces a natural motion without jerking or having the appearance of mechanical movement.

The figure may be a plane flat board, or plywood, or plastic, onto which the details of a picture of the object may be secured or printed, or

2

the figure may be molded to the shape of the object it is intended to simulate.

In the specifications, I have described in precise detail a preferred form of my invention so that the construction may be more easily understood by those skilled in the art to which this invention pertains. The construction may be modified in many respects without departing from the principles underlying my invention. I have not attempted to show all possible modifications which may fall within the scope of the claims which set forth my invention. The precision of the specifications is not intended to limit the scope of my patent.

15

Specifications

Referring to the drawings, particularly to Figs. 1, 2 and 3, I have shown the object 1 having the profile of a duck mounted at the rear on the axle 2 which passes through the aperture 3. Cams 4 and 5, one on each side of the parallel side surfaces of the figure, have end faces which engage the antifriction washers 6 and 7 which rotatably engage the object at each side as at 8 so that the cams may freely revolve on the axis 10 with the axle 2 to which the cams are secured. The oblique plane end surface of each cam is spaced parallel to the oblique plane end surface of the other cam and at a distance apart so that the parallel sides of the object and the anti-friction washers may move between the end cam surfaces as the cams are revolved by the axle. The wheels 12 and 13 secured to the ends of the axle provide sufficient traction on the floor over which they are rolled to rotate the cams and thus cause the object to waddle.

The front end of the object is preferably provided with the eye 14 which loosely fits over and slides on the guide bar 15 which may be tiltably mounted on the side frames 16 and 17, the rear ends of which are secured to the bearings 19 and 20 which are apertured to receive the axle 2.

The front ends 21 and 22 of the side frames are secured to the king pin bearing 23, the aperture 24 of which receives the king pin 25 which also engages the tongue piece 26 to which the front axle 27 is secured. The front wheels 28 and 29 are bored to freely revolve on the ends of the axle and the tongue piece is notched at 30 to receive the tongue 31 which is swingingly secured therein at one end, by the pin 32. The opposite free end 33 of the tongue is provided with the handle 34 for drawing the device along the floor or other surface.

55 In the modification shown in Figs. 4 and 5, I

have shown the figure 1' as conforming to the shape of a duck and being provided with a center boss 1a which is provided with flat plane sides 35 and 36 which are a substitute for the flat plane surfaces of Fig. 1 in engaging the end surfaces of the cams to cause the figure to waddle.

The sides 37 and 38 of the figure may be notched or cut out at 39 and 40 to clear the axle.

2. The object may be hollow and the boss 1a may depend from the inner top interior at the center.

Referring particularly to Fig. 3 of the drawings, I have shown the tilting angle A as represented by the broken lines of extreme travel on a vertical plane and the swinging angle as B; the extremes of travel on a horizontal plane are shown by broken lines.

To prevent binding and yet permit substantially no lost motion in the aperture 3, I have countersunk the sides as at 1c and 1d so that the object rests on a knife edge annulus rather than a cylindrical bore.

While the waddling motion caused by the rotation of the cams seems best suited to the motion of a duck, other objects may be given a similar motion by the cams and structure herein disclosed.

Having thus described a preferred embodiment of my invention, what I claim as new and desire to secure by Letters Patents is set forth in the following claims.

I claim:

1. In a toy figure comprising a wheeled frame and a figure movable in relation to the frame, said frame having wheels on which the toy figure is moved along, the wheels being secured to an axle supporting the figure and provided with cams secured to rotate with the wheels and provided with oblique cam faces for engaging substantially parallel faces on said figure to tilt and swing the figure in relation to the frame and a transversely disposed guide secured to the frame for supporting the front end of the figure to permit the figure to slide from side to side on said guide while tilting to impart a waddling motion to said figure.

2. In a toy figure comprising a wheeled frame and a figure movable in relation to the frame, said frame having wheels at the front and rear on which the toy figure is moved along, the rear wheels being secured to an axle supporting the rear of said figure and provided with cams secured to rotate with the rear wheels and pro-

vided with oblique cam faces for engaging substantially parallel faces on said figure to tilt and swing the figure in relation to the frame and means on said frame supporting the front end of said figure to permit the front end to swing from side to side in relation to said frame while tilting to impart a waddling motion to said figure.

3. In a toy figure comprising a wheeled frame and a figure movable in relation to the frame, said frame having wheels at the front and rear on which the toy figure is moved along, the rear wheels being secured to an axle supporting the rear of said figure and provided with cams secured to rotate with the rear wheels and provided with oblique cam faces for engaging substantially parallel faces on said figure to tilt and swing the figure in relation to the frame, means on said frame supporting the front end of said figure to permit the front end to swing from side to side in relation to said frame while tilting to impart a waddling motion to said figure, said figure having sides notched to receive said axle so that the sides may extend below the axle when the figure is tilted.

4. In a toy figure comprising a wheeled frame and a figure movable in relation to the frame, said frame having wheels at the front and rear on which the toy figure is moved along, the rear wheels being secured to an axle supporting the rear of the figure and provided with cams secured to rotate with the rear wheels and provided with oblique cam faces for engaging substantially parallel faces on said figure to tilt and swing the figure in relation to the frame, means on said frame supporting the front end of said figure to permit the front end to swing from side to side in relation to said frame while tilting to impart a waddling motion to said figure, said cams engaging the parallel sides of a center boss in said object to tilt and swing said object in relation to the frame.
